UNITED STATES PATENT OFFICE

2,086,204

FLOOR SURFACING MACHINE

Oscar L. Anderson, Los Angeles, Calif.

Application May 17, 1933, Serial No. 671,509

7 Claims. (Cl. 51—175)

This invention relates to surfacing and finishing machinery and has for an object the provision of a portable machine for rubbing, sanding and/or polishing wherein the portion of the machine which performs the rubbing, sanding and/or polishing operation is in the form of a reciprocatory member instead of a rotary member as in the case of the more conventional machine of this general class.

10. A more detailed object of the invention is the provision of a surfacing machine of the general character indicated which includes a block adapted to operate in conjunction with or actuated to carry a suitable detergent, rubbing or sanding material or polishing material, and mounted upon the frame of the machine through the expedient of a suitable track or guideway, or any suitable means for imparting reciprocatory motion to the block upon the track so as to effect the desired rubbing, scouring or polishing operation.

Another object is to provide novel means whereby the reciprocatory head is slidably mounted upon the frame of the machine.

25. Another object is to provide a surfacing machine of the general character described wherein the surfacing block i. e., the member which engages the surface to be treated, extends beyond the edges of the frame of the machine, the importance of this feature being that it permits the entire front or other surface being treated to be engaged by the operating member, even into the corners and closely adjacent the juncture of the wall with the floor.

35. A further object is to provide a surfacing block for use in conjunction with a surfacing machine of the general type indicated, in which novel means are employed for removably securing a strip of sand paper or the like in operative position upon the block.

40. A still further object is to provide novel means for mounting the surfacing block upon the reciprocatory head of the machine whereby replacement of the block by another carrying a fresh supply of sand paper may be effected with the utmost facility.

45. Another object is to provide a surfacing machine having the above and other characteristics which is of simple and rugged design which is relatively inexpensive to manufacture and operate and which can be relied upon to perform its intended functions with the utmost efficiency.

50. Other objects, advantages and features of invention may appear from the accompanying

drawings, the subjoined detail description and the appended claims.

The accompanying drawings illustrate the invention in the form I at present deem preferable.

Figure 1 is a top plan view of the machine embodying the principles of the present invention.

Fig. 2 is a view in side elevation.

Fig. 3 is a compound longitudinal vertical sectional view, the plans of section being indicated by the lines 3—3 of Fig. 1 and the direction of view by the arrows.

Fig. 4 is an elevation of the front end of the machine.

Fig. 5 is a top plan view of the operating member or sanding block. This view may be considered an original sectional view taken on the line 5—5 of Fig. 4 with the direction of view as indicated by the arrows.

My improved surfacing machine comprises a frame 6 preferably in the form of a flat metal plate and supported at the after end upon preferably a plurality of wheels 7 each of which is journalled as by an axle 8 in a bracket 9 rigid with the frame 6. A guiding way 11 is provided adjacent the forward end of the frame 6 through the expedient of a pair of opposed tracks 12 each of which is preferably closely adjacent the associate lateral edge of the frame or plate 6 and secured to its under surface so as to extend downwards therefrom. Each track 12 is provided with a shoulder 13 defining a surface which faces downwards so as to permit the nut 14 on a screw 16 or its equivalent to be tightened against the shoulder 13 and thereby rigidly clamp the track 12 against the plate 6. The lower portion of each track 12 is offset inwards thereby providing another shoulder 17 which defines an upwardly facing surface, and each of these surfaces or shoulders 17 is engaged by the under surface of an offset portion 18 of a rail 19, the purpose being to mount the rails 19 for reciprocatory motion below the under surface of the plate 6.

These rails 19 are rigidly affixed to the upper surface of a plate 21 and cooperate therewith to define the reciprocatory head 22, to which the 45 polishing, sanding or scouring block 23 is adapted to be removably secured. The rails 19 are so spaced that they are retained in sliding engagement with the vertical inner faces 24 of the offset portions of the rails 12 so that the reciprocatory head 22 is restrained against lateral movement with respect to the frame 6, but is permitted free reciprocatory motion longitudinally of the frame 6, moreover the plate 21 slidably engages the under surfaces of the tracks 12 50 55

while the offset portions 18 of the rails 19 engage the upper surfaces of shoulders 17 of the tracks 12 so that vertical movement of the head 22 with respect to the frame 6 is likewise prevented.

A plurality of pins 26 extend rigidly downwards of the plate 21, each pin being provided with a shoulder 27 at a predetermined distance above the lower end thereof which shoulder can more conveniently be provided by threading a nut 27' onto the pin 26 until it contacts the under surface of the plate 21 and by utilizing nuts 27' all of which are of the same thickness uniform spacing of these shoulders from the under surface of the plate 21 will be assured, preferably the pins 26 are arranged in a plurality of rows extending transversely with respect to the machine, two such rows being illustrated in the drawings although it should be understood that I do not wish to be limited to any precise number of such rows of pins. Each row of pins 26 is adapted to engage a rubbing, scouring, sanding, or polishing block 23, the upper surface 29 of which is provided with a plurality of sockets 31, the number of which corresponds to the number of pins 26 in each row with all the pins 26 of one of the rows adapted to be received within the socket 31 of one of the blocks 23 so that the block 23 is removably engaged upon the under surface of the reciprocating head 22.

To the upper surface of the plate 21, intermediate and parallel to the rails 19 are a pair of spaced racks 36 each of which has teeth 37. Associated with each rack 36 is a sector gear 38, the teeth 39 of which enmesh the teeth 37 of the associated rack 36. Each of the sector gears 38 is carried by a trunnion 41 which is mounted for rocking movement in a bearing 42 upon the upper surface of the plate 6 in which a suitable aperture 43 is provided for the sector gears 38 to extend downwards therethrough. Secured to the inner end of each of the trunnions 41 is a bar 44 and these bars are held in spaced parallel relation by pins 46 and 47, and adjacent their ends. The bar 44 extends to both sides of the aligned axes of the trunnions 41 that cooperate with each other to define a rocker arm to which the sector gears 38 are rigidly secured. The pin 47 at the upper end of the rocker arm 44 serves as a crank pin, inasmuch as it is engaged within a bearing 48 at one end of a connecting rod or pitman 49, the bearing 51 at the other end of which is suitably engaged upon a crank pin 52 which is rigidly and eccentrically mounted upon and between a pair of axially aligned disks 53, each of which is rotatably carried by a suitable bearing 54 upon the upper surface of the plate 6. The shaft 56 carrying one of the disks 53 is extended far enough to receive a sprocket 57 which is engaged by a chain or belt 58 and this chain is also engaged on the sprocket 59 carried by the shaft 61 of a motor 62 which in turn is mounted upon a suitable base 63 which is retained in elevated position above the plate 6 by preferably a pair of supporting plates 64.

Thus it may be seen that when the motor 62 is energized, suitable electrical conductors (not shown) being connected therewith for this purpose, the disks 53 will be rotated, thereby imparting reciprocatory motion to the pitman 49 which in turn moves the rocker arm defined by the two bars 44 back and forth; and through the interengagement of the sector gears 38 with the racks 36 this motion of the rocker arm will result in longitudinal reciprocatory motion of the

head 22 and the block or blocks 23, as the case might be, that are carried thereby.

As a precautionary measure the lower pin 46 of the rocker arm extends relatively loosely through a rigid loop or eye 71 which is affixed to the upper surface of the plate 21 so that reciprocatory motion of the head 22 will be assured even in the event of failure of the interengagement of either or both of the sector gears 38 with their respective racks 36.

Means are provided upon the block 23 for removably securing a sheet of polishing, grinding or smoothing material such as a sheet of conventional sand paper to the surface of the block, this stripping means comprises a pair of rigid strips 72 and 73 mounted upon the upper surface of the block 23 adjacent each of two parallel edges thereof, preferably the front and rear edges instead of being clamped tightly against the block, however these strips are spaced slightly therefrom, their ends 74 being deflected downwards toward the block so as to provide suitable supports for the strips, the purpose of this structure is to permit the ends 76 and 77 of a sheet 78 of sand paper or analogous material to be inserted under the strips as will readily be understood. Associated with one of the strips, preferably the strip 73 adjacent the forward edge of the block is a bar or strip 81 which is pivotally mounted at one end upon a bracket 82 adjacent one end of the block 23. This strip 81 is disposed in a vertical plane and immediately above a groove 82 (see Fig. 3) which preferably is disposed immediately behind the after edge of the strip 73. A clip 83 is rockably mounted upon the upper surface of the strip 73 adjacent the other end of the block 23, this clip 83 being adapted to be turned so as to engage the upper edge of the strip 81 when the strip 81 is lowered far enough to cause the lower edge to enter the groove 82. The strip 78 of sand paper is thereby attached in operative position to the block 23, but first having its end 76 thrust under the strip 72 which it should be explained is spaced from the upper surface of the block 23 only far enough to permit such insertion, hence after the end 76 of the sand paper has been so inserted, sufficient friction will be established therewith by the strip 72 that this end of sand paper will be retained as positioned. The strip 78 of sand paper is folded around the under surface of the block 23 thus bringing the other end 77 upwards to permit its being similarly thrust under the strip 73. This end 77, however, should be thrust far enough so that it extends over the groove 82, whereupon by lowering the pivoted strip 81 a fold of the sand paper can be forced downwards into the groove, thereby imposing a considerable degree of tension upon the sand paper and firmly locking the end 77 thereof in position. It should be understood that a pivoted strip such as the strip 81 may be employed in conjunction with both ends of the strip of sand paper if desired, but it is not deemed necessary for the reason that the tension which one such pivoted strip imposes upon the sheet of sand paper will cause the opposite end of the sheet to bind itself between its associated rigid strip 72 and the upper surface of the block 23. Sand paper is inherently relatively stiff and the tension imposed upon the sheet tends to pull the end 76 toward the associated lateral edge of the block 23 and around the upper corner at that edge of the block, however, owing to the stiffness of the sand paper this tendency to move around the corner causes the upper, i. e., the rough surface of this end 76 to

to be pressed quite tightly against the under surface of the strip 12, this I have found can be relied upon to anchor the end 16 of the sand paper with sufficient firmness to permit dispensing with 5 a pivoted strip 31 at each end of the strip of sand paper.

It will be observed by observation of Figs. 1 and 4 that the block 23 is the widest portion of the entire machine, thus causing the ends of block 10 23 to project past the lateral edges of the frame 26, the importance of this feature is that it permits the floor or other surface being sanded, polished or otherwise treated to be engaged by the under surface of the block 23 right up to the base board 15 or molding and actually into the extreme corners of the floor, in this manner, I have overcome one of the inherent disadvantages of floor polishing machines which employ rotary operating members, the use of which requires that the extreme 20 edges of the floor be treated by hand, because of the fact that such portions of the floor are inaccessible to machines of this type. Contradistinct with rotary polishers the reciprocatory polishing head of my machine, presenting as it does 25 the widest portion of the machine, is able to establish operating engagement with all portions of a floor or other surface, thus obviating the necessity of treating any portion of the floor by hand.

30 In this specification it is understood that the block 23 may be made in the form of any suitable surface engaging member such as a roughing tool, a scrubbing brush, different types of steel brushes, sand or sanding blocks or any suitable 35 polishing and buffing block, each of which to be provided with the plurality of sockets 31, to be received on the pins 26 and it is understood that the use of any one of such blocks 23 shall include any of the other styles or types of blocks here- 40 inbefore referred to.

I claim:

1. A surfacing machine comprising a wheeled frame, means providing a guiding way on said frame, a head slidably mounted in said way, 45 a block releasably mounted on said head, surfacing material carried by said block, rack teeth on said head, a rocker arm mounted on said frame for rocking movement, a sector gear rigid with said rocker arm and having teeth enmeshed with 50 said rack teeth, and a reciprocating connecting rod extending from said rocker arm for reciprocating said rocker arm.

2. A surfacing machine of the character described, comprising a wheeled frame, a plurality of parallel tracks disposed therebelow, each of said tracks having a shoulder thereon defining an upwardly facing surface extending longitudinally thereof, a head slidably engaging the under surfaces of all of said tracks, means rigid 55 with said head and slidably engaging each of said tracks along the upper surfaces thereof, a block

secured to the under surface of said head, and surfacing material carried by said block.

3. A surfacing machine comprising a wheeled frame, means providing a guiding way on said frame, a block, surfacing material carried by said block, means slidably mounting said block in said way, said block being greater in at least one dimension than the width of said frame, rack teeth associated with said block, a gear mounted on said frame for rocking movement 10 and having teeth enmeshed with said rack teeth and a reciprocating rod extending from said gear for rocking said gear and reciprocating said block.

4. A surfacing machine comprising a frame; a wheel means supporting one end of said frame; 15 a guiding way on said frame; a block; surfacing material carried by said block; means slidably mounting said block in said guiding way; rack teeth associated with said block; a gear rockably mounted on said frame and having teeth 20 enmeshed with said rack teeth; a connecting rod connected to said gear; and means for imparting movement to said connecting rod to rock said gear.

5. A surfacing machine comprising a frame; 25 wheeled means for supporting one end of said frame; means providing a guiding way on said frame; a head slidably mounted in said way; a block detachably connected to said head; surfacing material carried by said block; rack teeth 30 on said head; a gear rockably mounted on said frame and having teeth enmeshed with said rack teeth; a connecting rod extending from said gear; and means for imparting reciprocatory movement to said connecting rod to rock said 35 gear.

6. A surfacing machine comprising a frame; wheeled means supporting one end of said frame; means extended from said frame to form a guiding way; a head slidably mounted in said 40 way; a plurality of pins extending from the underside of said head; a block having sockets to receive said pins; surfacing material carried by said block; a gear rack on said head; a gear rockably mounted on said frame and having 45 teeth enmeshed with said gear rack; a connecting rod connected to said gear; and means mounted on said frame to reciprocate said rod to rock said gear and move said head along said guiding way.

7. A surfacing machine comprising a frame; a guiding way on said frame, a head slidably mounted in said way; surfacing material operatively connected to said head; rack teeth associated with said head; a gear rockably mounted 55 on said frame and having teeth enmeshed with said rack teeth; a connecting rod connected to said gear; and means for reciprocating said connecting rod to rock said gear.

OSCAR L. ANDERSON.
